Alexander D. McLean.

UNITED STATES PATENT OFFICE.

ALEXANDER D. MCLEAN, OF CHICAGO, ILLINOIS.

MACHINE FOR SHAVING CURVED STEREOTYPE-PLATES.

SPECIFICATION forming part of Letters Patent No. 314,391, dated March 24, 1885.

Application filed April 8, 1884. (No model.)

To all whom it may concern:

Be it known that I, ALEXANDER D. MCLEAN, residing at Chicago, in the county of Cook and State of Illinois, and a citizen of the United States, have invented certain new and useful Improvements in Machines for Shaving Curved Stereotype-Plates, of which the following is a full description, reference being had to the accompanying drawings, in which—

10 Figure 1 is a cross-section on line $x-x$ of Fig. 2; Fig. 2, a top or plan view with the plate and breaker removed; Fig. 3, a plan view of the feeder and breaker; Fig. 4, a side view of the clamp for the feeder and breaker; Fig. 5, 15 a cross-section on line y of Fig. 3 enlarged; Fig. 6, a side view of another form of clamp.

The object of this improvement is to facilitate the shaving of curved stereotype-plates in shaving-machines, and have the act 20 performed without injury to the type or letter faces, and also to permit of the easy insertion and removal of the stereotype-plates from the machine; and its nature consists in the improvements hereinafter claimed as new.

25 In the drawings, A indicates the frame of the machine; B, the concave for receiving and holding the stereotype-plates; C, the shaving-blade; D, the stop-plate; E, curved stereotype-plate; F, the feeder and type-protector; 30 a, clamping head or bar attached to the front or leading edge of the breaker; b, a groove in the head a for preventing the head from injuring any projecting type or figure faces; c, cross-rod for the tail end of the breaker; d, 35 guides or stops for holding the clamp a in position; e, projecting ends of the clamp a.

The frame A, concave B, and cutter or shave C are made in the usual manner, and fitted to receive stereotype-segments of the size and 40 curve suited to the cylinder to which the finished stereotype-plates are to be applied. The concave B is provided with the stop-plate D, which prevents the moving of the plate within the concave when the shave is applied, and at 45 the ends of this plate D the stops or guides d are applied, beneath which the ends e of the clamp a pass. These stops are bent down, as shown in Fig. 1, and in this form they prevent the clamp a from getting out of position, or so as 50 to come in contact with the rotary shave C. The clamp or head a is preferably made of two bars, as shown, as by this construction

the feeder and type-protector F is firmly, evenly, and strongly attached thereto; and in order to prevent injury to any projecting letters or figures on the surface of the stereotype-plate this head or clamp is provided with the groove b, so that the plates may pass under the head or clamp and at the same time be firmly held without injuring or marring them.

The feeder F can be made of the material used for tympan-sheets. Its opposite or tail end is provided with the rod c, which, as shown, is made to project so that it can readily be grasped.

In use the feeder and type-protector is laid on the machine in about the position shown in Fig. 1, when the leading edge of the stereotype-plate is placed against the clamp a, and the operator, by pressing his body against the feeder, can control the insertion of the plate E at pleasure. A counter-weight or treadle can be used, if desired, for controlling the insertion and release of the plates; but ordinarily the movement of the feeder will be sufficiently controlled by the operator without other devices. The plate is easily fed into position for shearing, and as its insertion carries the head a along the protector is evenly and smoothly fed in between the concave and the type-faces, so that no injury whatever occurs to the faces of the type, and the movement of the stereotype-plate is easily controlled and regulated. By this arrangement the use of brass linings for the concave is avoided; also the insertion of paper, which has been found difficult and insufficient. The feeder and type-protector adds to the utility of the machine in respect to inserting, controlling, and releasing the plates, and handling the plate with more ease and certainty than has heretofore been done.

It will be understood that the plates are usually too hot to be handled by the naked hand when they are placed in the shaving-machines, and for this reason, among others, their manipulation in inserting them in this class of machines has heretofore been difficult, and particularly so whenever a paper lining has been attempted to be used.

The heavy pressure of the knife in shaving the plate has heretofore had the effect of crushing any projecting letters or parts of cuts, but by the use of this protector such slight pro-

jections become embedded therein and remain uninjured by the pressure of the shaving-knife. The application of the shaving-knife to hot plates also has a tendency to cause them to fit 5. the concave so closely as to frequently adhere or become set in position, thus requiring the application of chisels or other tools to loosen them; but by using the feeder and protector F the plates do not become set, and by taking 10 hold of the rod c they can, when finished, be as readily withdrawn as they are inserted. The use of my improvement greatly facilitates the shaving of these plates besides the protection it affords to the type-faces and the 15 ease of inserting and retracting the plates. A clamping form of the head a, which enables the feeder to be readily inserted and firmly held, is the most desirable construction for this purpose; but I do not limit myself to one made 20 of two pieces, as by providing a proper recess beneath the stop-plate D different constructions may be used, and the clamp can also be made of a single bar. One form of making the clamp in a slightly-different manner is 25 shown in Fig. 6, in which the clamp is made in two pieces with their adjoining faces running diagonal to form the opening for the end of the feeder, which gives a wider clamping-surface.

30 The feeder and type-protector can be made of

cloth or other fabric, strong paper, or a soft-metal sheet of tin or other material, the only requisite being that the material shall be of sufficiently yielding nature to allow the face of the type to embed therein without injurious effects, and of sufficient strength to withstand the strain of inserting the plates. 35

What I claim as new, and desire to secure by Letters Patent, is—

1. In a machine for shaving curved stereotype-plates, the type-protecting feeder F, interposed between the concave bed and the type-face of the inserted plate, substantially as described. 40

2. The combination of the head a, having the grooves b and concaved bed B, with the feeding and type-protecting sheet F and guides or holders d, substantially as described. 45

3. The clamping bar or head a, having the groove b, in combination with the feeding type-protector F, for preserving the form of the type-faces, substantially as specified. 50

4. The combination of the head a, feeding-protector F, and rod c, substantially as described.

ALEXANDER D. MCLEAN.
